ROTATING DISK RACING GAME

Clarence F. Boreszewski, Camden, N. J.

Application May 30, 1945, Serial No. 596,731

3 Claims. (Cl. 273—141)

1

This invention relates to games, and more particularly to a racing game employing a stationary game board or base and a movable member associated therewith for use in determining the winners of each race in the course of play.

The primary object of my invention is to provide an improved racing game which involves factors simulating very closely conditions found in actual races, such as horse races.

More particularly, it is an object of my invention to provide an improved racing game in which players may make selections of probable or preferred winners on a basis similar to actual horse races and in which winning players will be "paid off" under odds simulating those found in true races.

Another object of my invention is to provide an improved racing game as aforesaid in which any number of players may participate without limit and regardless of the size of the game board.

Still another object of my invention is to provide an improved racing game as aforesaid of which the rules and course of play are very simple and easy to follow.

A further object of my invention is to provide an improved racing game as set forth above which will not lag in interest and which will afford a high degree of entertainment.

It is also an object of my invention to provide an improved racing game such as described above which is comprised of a minimum number of parts, which can be manufactured at low cost and assembled with great ease, which is sturdy in construction, which will occupy a minimum of space, and which is positive in action.

According to one form of my invention, the game includes a stationary disc or other suitable base and a rotary member, which may also be a disc, carried by said base. The base is divided into a plurality of concentric, annular areas, in turn divided into a plurality of radially aligned, equi-angular sectors each pertaining to a particular horse, dog, or other "participant" in the race. Each sector of one of the annular areas (for example, the middle one) is marked with the name of a horse or other similar participant. Each sector of another of the annuli (for example, the outermost one) is subdivided circumferentially into three subdivisions one of which is marked "Win," a second "Place" and the third "Show." These subdivisions may be termed "selection boxes" and are used by players of the game to make selections of anticipated winners according to whether they select a particular horse or the like of any sector to come in first,

2

second or third in any race. Each sector of a third annular area (for example, the innermost one) is subdivided into three radially-displaced, circumferentially-extending rows, in turn subdivided into a plurality of radial columns of blocks each of which is marked with a number indicating the odds to be paid for the associated horse. One of the aforesaid three rows indicates the odds to be paid from a "bank" on a horse coming in first to "Win"; another of said three rows indicates the odds to be paid on that horse if it comes in second to "Place"; and the third of said rows indicates the odds to be paid on the horse if it comes in third to "Show." Thus, the three circumferentially-extending "odds" rows of the third mentioned annular area are correlated, respectively, with the "Win," "Place" and "Show" selection boxes of the respective sectors of the second mentioned annular area.

The rotary member carried by the base constitutes an indicator for indicating the several winning horses and their respective positions at the conclusion of any race. For this purpose, the rotary member has three indicators or markers numbered "1," "2" and "3" spaced from each other circumferentially on angles equal to or greater than the angle of each of said sectors of the above-mentioned annular areas. Thus, when, in the course of play, the rotary member is spun or rotated (either manually or by a suitable power device) and it eventually comes to a stop, its three indicators will point to radial "odds" columns of three different sectors, the horse of the sector opposite the indicator "1" being considered the "Win" horse, the horse of the sector opposite the indicator "2" being considered the "Place" horse, and the horse of the sector opposite the indicator "3" being considered the "Show" horse.

The game also includes a plurality of tokens or play money which may be used in playing the game. Any number of players may participate and each or any of them may make any number of selections he chooses (within limits prescribed by the players themselves) by merely placing in the appropriate selection box or boxes of any of the sectors a token to serve as a marker or indicator of his selection. When all the players who wish to do so have made their selections, the rotary member is twirled and permitted to come to a stop. All players who have selected horses other than the three winning ones forfeit to the bank tokens which they played. As to the winning players, however, the bank pays them a num-

ber of tokens according to the odds indicated in the appropriate "odds" block.

In another and preferred form of my invention, the outermost and the intermediate ones of the concentric, annular areas may be in the form of complete annuli, if desired, but the innermost area (i. e., the one subdivided into the "odds" blocks) is preferably only a partial annulus concentric with the other two and only long enough to embrace three of the sectors into which the two complete annuli are divided. The last mentioned area, or partial annulus, is itself divided into three similar sectors of which one is designated the "Win" sector and the three circumferential rows of "odds" blocks therein are all marked with appropriate odds indications; another of said last mentioned, three sectors is designated the "Place" sector and only two circumferential rows of its "odds" blocks are marked with odds indications; and the third of said last mentioned sectors is designated the "Show" sector with only one of its circumferential rows of "odds" blocks marked with appropriate odds indications. Each of the several sectors of the outermost and intermediate concentric areas is marked with a number or other suitable designation to go with the participant of that sector. The rotary disc is divided into a like number of sectors which are similarly marked with a like number of corresponding designations, as well as with a radial indicator in each of its sectors. Thus, when the rotary disc comes to a stop after having been rotated, the sector thereof having its indicator pointing to the aforesaid "Win" sector indicates the participant coming in first, and the radial column of three blocks opposite which the indicator comes to rest shows the odds to be paid for the token played on that participant to Win, Place or Show. Similarly, the sector of the rotary disc having its indicator pointing to the aforesaid "Place" sector indicates the participant coming in second, and the radial column of two blocks opposite which the indicator comes to rest shows the odds to be paid for the token played on that participant, in one case to Place and in the other to Show. Finally, the sector of the rotary disc having its indicator pointing to the aforesaid "Show" sector indicates the participant coming in third, and the single block opposite which the indicator comes to rest shows the odds to be paid for that participant to Show. The plays or selections are made with the tokens, as in the first modification described above, and the game proceeds in a similar manner for each race.

The novel features that I consider characteristic of my invention are set forth with particularity in the appended claims. The invention itself, however, both as to its organization and method of play, as well as additional objects and advantages thereof, will best be understood from the following description of two embodiments thereof, when read in connection with the accompanying drawings in which

Figure 1 is a plan view of one form of game according to my invention,

Figure 2 is a central, sectional view thereof,

Figure 3 is a plan view of another and preferred form of game according to my invention, and

Figure 4 is a plan view of several of the tokens or play pieces forming part of the game.

Referring more particularly to the drawings wherein similar reference characters designate corresponding parts throughout, there is shown, in Figures 1 and 2, a racing game having a sta-

tionary base A constituting a game board and provided with an upstanding pivot post B. Rotatably carried by the post B is a sleeve or cap C which is secured to a circular disc D, the disc D thus being rotatable on the post B relative to the base A. The base A is marked off by main circular markings E, F, G and H, such as lines, upstanding ridges, depressions, grooves or the like, into three concentric, annular areas J, K and L coaxial with the post B. A plurality of main radial markings M which extend clear through each of the annular areas J, K and L divide these annular areas into a plurality of substantially equi-angular, radially aligned, correlated sector divisions or groups N, each division including one sector of each of the areas J, K and L, and six such sector groups or divisions being shown by way of illustration, it being understood that any number of such groups may be provided as may be found desirable or feasible.

In each division or sector group, the sector of the annular area J is subdivided by two radical lines P into three "selection boxes" Q one of which is marked "Win," a second "Place" and the third "Show." The boxes Q serve as subdivisions in which players of the game may make selections (in a manner more fully described hereinafter) not only of the participants in the race they anticipate will win, but also the order in which they anticipate the three leading participants will appear at the conclusion of each race or play. Each sector K' of the annular area K bears the name or other identifying characteristic of one participant. The innermost annular area L has each of its sectors subdivided by a pair of auxiliary, circular lines R into three radially-adjacent, circumferentially extending rows of subdivisions, and by a plurality of radial lines S into a plurality of circumferentially-adjacent, radially extending rows of subdivisions to provide a plurality of blocks T which may be termed "odds blocks." In each of the blocks T is a numeral indicating the odds payable to a player in accordance with (a) whether the participant of the race named in the correlated sector was selected by the player, and (b) the actual position of that participant at the conclusion of a race or play, assuming, of course, that that particular participant finished first, second or third.

To determine which participants (for example, horses) are the winners, the rotary disc D is divided by radial lines V into the same number of equi-angular sectors W as there are sectors in the areas J, K and L, or at least into three such sectors. These three sectors, or any three of them if there are more than three, are provided with outwardly directed, radial indicators, such as the arrows Y, which are marked, respectively, with the numerals "1," "2" and "3" to indicate the horse coming in first to "Win," the horse coming in second to "Place," and the horse coming in third to "Show." Thus, when the disc D has come to rest after it has been rotated, the arrow Y marked "1" indicates the sector where the horse finishing first is to be found; the arrow Y marked "2" indicates the sector N where the horse finishing second is to be found; and the arrow Y marked "3" indicates the sector N where the horse finishing third is to be found. At the same time, the odds payable to the players who selected the three winning horses will be found in the particular radial columns of blocks T of the winning horses' sectors to which the three arrows Y point.

The game may be played in the following manner with the aid of differently colored or differ-

ently marked tokens Z or the like, each representing a different value or denomination;

At the beginning of the game, the tokens are divided equally among all the players each of whom then contributes a prescribed number of tokens to a common fund called the "bank." The players, or any of them, then select their horses for a given race and indicate their selections and the positions they anticipate their selected horses will occupy at the conclusion of the race by placing on the appropriate selection boxes Q the tokens each wishes to play on the correlated selected horses. The disc D is then spun or rotated and, when it comes to rest, its arrows Y will not only indicate the three winning horses, but also the odds payable from the bank to the players who selected such horses and in correspondence with the relative positions of these horses in the race. Players who have selected non-winning horses will, of course, forfeit their tokens to the bank. Should the bank lose or pay out all its tokens during the course of a game, the players will then again each make a contribution to replenish its funds.

By way of illustration, let it be assumed that, in a particular race or play, one player wishes to play a token of a particular color or denomination on Duna to win, another player wishes to play a token of one color or value on Bonnie Gray to win and a token of another color or value on Duna to place, and a third player wishes to play a token of still another color or value on Sorrel Queen to show. The first player makes his selection by placing a token Z of appropriate denomination in the "Win" selection box Q of the Duna sector N; the second player makes his selection by placing an appropriate token Z in the "Win" selection box Q of the Bonnie Gray sector N and a suitable token in the "Place" selection box Q of the Duna sector; and the third player makes his selection by depositing a suitable token Z in the "Show" selection box Q of the Sorrel Queen sector N. The disc D is then rotated and permitted to come to a stop to indicate the three winning horses and the odds paid by each.

Let it be assumed, now, that the disc D has stopped in the position shown in Figure 1 with the arrows Y pointing to the most counter-clockwise radial columns of odds blocks T in the sectors opposite these arrows. The arrow Y marked "1" shows that Duna came in first to pay odds of 6:1 for Duna "Win" selections as shown by the outermost one of the blocks T, to pay odds of 4:1 for Duna "Place" selections as shown by the intermediate block T, and to pay odds of 3:1 for Duna "Show" selections as shown by the innermost block T of the particular radial column to which the arrow marked "1" points. Hence, the first mentioned player will receive from the bank six tokens of the color played by him, while the bank takes the token played by this player, and the second mentioned player will receive from the bank four tokens of the color played by him for his particular selection of Duna, the bank taking the token he played on this horse.

The arrow Y marked "2" shows that Silver Streak came in second to pay odds of 2:1 for "Place" selections for that horse and even money for "Show" selections. Since, however, no plays or selections were made on Silver Streak, the bank neither receives nor pays out any tokens in this case.

Finally, the arrow Y marked "3" shows that Sorrel Queen came in third to pay odds of 2:1

for "Show" selections. Hence, the third mentioned player will receive from the bank two tokens of the color played by him while giving up to the bank the token which he used in making his selection. As for the selection made by the second mentioned player on Bonnie Gray, since this horse was not among the first three, that player must forfeit to the bank the token he played on this horse.

In the modification shown in Figure 3, the concentric, annular areas J and K are divided into sectors similarly to the corresponding areas of the game board of Figure 1. However, each sector N is provided with a numeral or other suitable marking Ya by means of which the horse of the correlated sector may be identified. The area L, in this modification, while concentric with the areas J and K, is, however, only of a length sufficient to embrace three of the sectors N, its area in one of the sectors N1 being divided into three circumferential rows of odds blocks T, respectively marked -W- for Win, -P- for Place and -S- for Show; its area in another sector N2 being divided into only two such rows -P- and -S-; and its area in the third sector N3 having only one such row -S-. Each of the sectors W on the disc D is also marked with a marking Yb (the latter markings corresponding in number and in identifying characteristics to the markings Ya) as well as with a radial indicator Y. In addition, the sector N1 is provided with a Win indicator, such as a flag X1, the sector N2 with a Place indicator, such as a flag X2, and the sector N3 with a Show indicator, such as a flag X3. With this modification of my invention, the markers or numerals Yb indicate the three winning horses and their relative positions at the end of each race. Thus, as shown in Figure 3, horse #4 (identified by one of the markers Ya to be Silver Streak) came in first; and since the related indicator Y points to the second from left, radial "odds" column of the sector N1, this horse will pay odds of 9:1 for Win selections, odds of 3:1 for Place selections, and odds of 2:1 for Show selections. The numeral "1" of the markers Yb shows that horse #1 (Get-away Fast) came in second; and the related indicator Y shows that this horse will pay odds of 4:1 for Place selections and odds of 3:1 for Show selections. Lastly, the numeral "3" of the markers Yb shows that horse #3 (Never Fail) came in third; and the related indicator Y shows that this horse will pay odds of 2:1 for Show selections.

From the foregoing description, it will undoubtedly be apparent to those skilled in the art that I have provided a novel racing game which is highly entertaining and which can be played by as many players as desire to play simultaneously. Although I have shown and described but two embodiments of my invention, many other modifications are possible. For example, the disc D may be motor driven instead of being arranged for manual operation. Also, instead of the disc D, an endless belt with suitably marked, radially extending pointers may be used. Moreover, the areas J, K and L need not necessarily be annular, nor need they be concentric. Many other changes will, without doubt, readily suggest themselves to those skilled in the art. Hence, I desire that my invention shall not be limited except insofar as is made necessary by the prior art and by the spirit of the appended claims.

I claim as my invention:

1. A racing game comprising a base having a plurality of concentric areas, said areas being divided into a plurality of radially aligned sectors, each sector of one of said concentric areas designating a different participant in any one race, each sector of another of said concentric areas being subdivided circumferentially into a number of subdivisions each of which designates a selection to be made by a player of the anticipated position of a particular participant in the race relative to the other participants therein at the conclusion of play representing said race, and each sector of a third of said concentric areas being subdivided into a like number of radially-adjacent, circumferentially extending rows within the sector, said rows being further subdivided into a plurality of radial columns of blocks extending through said number of rows, at least certain of said blocks bearing indications designating odds payable to a player in accordance with (a) the participant selected by him and (b) the actual position of said selected participant at the conclusion of said play.

2. A racing game according to claim 1 characterized by the addition of a rotary member on said base mounted for rotation on the common axis of said concentric areas, said rotary member having said number of indicators thereon for cooperation with the same number of different ones of said sectors, and said indicators

each having a different numerical marking associated therewith to indicate the order of finish of said number of said participants in said race.

3. A racing game according to claim 1 characterized in that said first and second named concentric areas have a like plurality of said sectors, the sectors of one of said first and second named concentric areas being differently marked for the purpose of identification, characterized further in that said third concentric area has only said number of said sectors, and characterized still further by the addition of a rotary member on said base mounted for rotation on the common axis of said concentric areas, said rotary member having as many indicators as there are sectors in said first and second named concentric areas, and said indicators being also marked for identification in correspondence with the markings of said marked sectors.
